UNITED STATES PATENT OFFICE.

JOHN L. HAMMOND, OF MACON, MISSOURI, ASSIGNOR OF ONE-HALF TO JOHN W. PATTON, OF MACON, MISSOURI.

CYLINDER-ROLLER FILM-STEADIER FOR MOVING-PICTURE MACHINES.

No. 12,985.

Specification of Reissued Letters Patent.

Reissued July 6, 1909.

Original No. 917,727, dated April 6, 1909, Serial No. 443,494. Application for reissue filed June 4, 1909.

Serial No. 500,230.

To all whom it may concern:

Be it known that I, JOHN L. HAMMOND, a citizen of the United States, resident of Macon, in the county of Macon and State of Missouri, have made a certain new and useful Invention in Cylinder-Roller Film-Steadiers for Moving-Picture Machines; and I declare the following to be a full, clear, and exact description of the same, such as will enable others skilled in the art to which it appertains to make and use the invention, reference being had to the accompanying drawings, and to letters of reference marked thereon, which form a part of this specification.

Figure 1 is an end view of the invention as applied. Fig. 2 is a perspective view of the invention showing the seat for holding the roller against the film. Fig. 3 is a section on the line 3—3, Fig. 4. Fig. 4 is a section on the line 4—4, Fig. 3.

The invention relates to means for steady-
ing the films of moving picture machines, having for its object to prevent the objection-
able jumping or quivering of the picture, which is held absolutely still, extending the
life of a film more than double, and extend-
ing the life of the machine, the invention
being capable of attachment to any moving
picture machine at small cost.

Other objects and advantages will here-
inafter appear.

In the accompanying drawings, illustrating the invention, the letter *a*, designates the film, having the usual marginal perforations; *a'*, and *b*, the feed sprocket wheels of the machine engaging such perforations.

c, is the film steadyng device comprising a hollow cylinder carrier *c'*, having a stand-
ard support *d*, at one end thereof, said sup-
port being secured at its lower end in suit-
able supporting bearings shown at *d'*. The
carrier *c'*, is pivotally mounted upon a re-
duced upper portion *f'*, of the standard *d*,
resting upon the shoulder *f''*, at the base of
such reduced portion, a set nut *g*, having
bearing against a short coil spring *g'*, fitting
around the upper end portion of the part *f'*,
and bearing at its lower end upon the car-
rier *c'*, serving when the spring is put under
tension by the set screw to check the free
movement of the carrier upon the standard
or to act in the nature of a brake upon such
movement.

h, is a friction roller of soft rubber or 55
other suitable material, said roller having at
each side thereof metal journal extensions
h', *h''*, provided with bearings in journal
blocks *i*, *i'*, mounted in vertical barrels *i'*, *i''*,
secured within the carrier at the end por- 60
tions thereof. Each barrel *i'*, is vertically
slotted at *j*, to allow movement of the exten-
sion *h'* therein, a coil spring *j'*, fitting in
the barrel and bearing at its lower end upon
the journal block, which bears at its lower 65
end upon the solid bottom *k*, of the barrel
having a threaded opening *k'*, for engage-
ment with the securing screw *l*. The coil
spring and journal block are slipped in from
the open upper end portion of the barrel, an 70
upper bearing piece *l'*, lying above the
spring and having a reduced portion *l''*, en-
gaging within the coils thereof. The upper
securing screw *m*, has engagement with a
depression *m'*, of the bearing piece whereby 75
all the parts are securely held in position.
The friction roller projects partly without
the cylinder carrier through a central slot *n*,
of its lower wall, such roller being held in
projected position by the action of the coil 80
springs *j'*, *j''*, and inward movement of the
friction roller, while being allowed, is re-
sisted by the action of such springs, whereby
the roller is held under spring tension.

In the application of the invention, the 85
cylinder carrier is turned upon its standard
support to one side toward the door of the
machine, and the film having been adjusted
in position, the cylinder carrier is turned
back toward the film, so that the rubber 90
friction roller will engage the same, said
roller bearing against a roller *o*, over which
the film passes, and against which it is
pressed by the rubber roller.

The cylinder carrier is allowed a slight 95
upward movement at its free end owing to
the coil spring *g'*, against which the set
screw *g*, has bearing, and as the carrier is
turned toward the film, this slight lift al-
lowed enables the carrier to engage at its free 100
end in stationary seat *p*, of the machine,
whereby the carrier and its friction roller
are securely held in position with the film
compressed by the rubber roller against the
lower roller *o*, to a slight extent, which is 105
sufficient to prevent any unnecessary move-
ment of the film and does not in any way
prevent its free passage or feed through

such rollers nor injure the film or negative in any way.

The use of the invention causes a steady pull on the film in one direction and will 5 result in a perfect picture upon the curtain or screen until the marginal holes of the film wear absolutely together.

Inasmuch as the film is prevented from playing backward and forward on the feed 10 sprocket wheels that engage with the marginal perforations, the life of these wheels, which are made of soft brass and are somewhat expensive, is largely extended.

Having thus described the invention, what 15 I claim as new and desire to secure by Letters Patent is:

1. In a roller film steadier for moving picture machines, an upright standard, a roller carrier pivoted at one end to the 20 standard to swing laterally with reference thereto, a friction roller in the carrier and a guide roller below the friction roller.

2. In a roller film steadier for moving picture machines, a guide roller, a swinging 25 roller carrier, and a friction roller in the carrier and capable of being swung therewith toward and away from the guide roller.

3. In a roller film steadier for moving picture machines, a carrier having a pivotal 30 support at one end thereof, and a spring-pressed friction roller mounted in said car-

rier, adapted to coöperate with the guide roller of the machine to steady the film and capable of swinging with the carrier upon the pivotal support as a center toward or 35 away from the film.

4. In a roller film steadier for moving picture machines, an upright standard having a reduced upper end portion and a shoulder at the base of said reduced portion, 40 a carrier pivotally mounted upon the reduced portion of said standard and resting upon said shoulder, a coil spring at the upper end of said reduced portion and bearing upon said carrier, a set screw engaging the 45 upper end of said reduced portion and bearing against said spring, a spring-pressed friction roller mounted in said carrier, adapted to coöperate with a guide roller of the machine to steady the film and capable 50 of swinging with the carrier upon said standard as a center toward or away from the film, and a seat for said carrier to retain it in position with the friction roller thereof in engagement with the film.

In testimony whereof I affix my signature, in presence of two witnesses.

JOHN L. HAMMOND.
